CLAIM

The ornamental design for a playpen for animal, as shown and described.

DESCRIPTION

FIG. 1 is a perspective view of the playpen for animal. FIG. 2 is a side view thereof. The other side view is identical to this side view and therefore the other side view is not shown.

FIG. 3 is a front view thereof. The back view is identical to the front view and therefore the back view is not shown.

FIG. 4 is a top view thereof.

FIG. 5 is a bottom view thereof.

FIG. 6 is an enlarged cutaway view of a corner portion of the playpen for animal shown in FIG. 1. All other corner portions shown in the drawings are identical; and,

FIG. 7 is an enlarged cutaway view of a midsection portion of the playpen for animal shown in FIG. 1. All other midsection portions shown in the drawings are identical. The dash dot dot dash lines shown in FIGS. 1, 6 and 7 form no part of the claimed design. The dash dot dot dash lines shown in FIG. 1 show the bounds of cutaway views FIGS. 6 and 7.
